[57] CLAIM

The ornamental design for an orthopedic cervical pillow, as shown and described.

DESCRIPTION

FIG. 1 is a top, front and right side perspective view of an orthopedic cervical pillow showing my new design; FIG. 2 is a bottom, rear, and left side perspective view thereof;

FIG. 3 is a front elevational view thereof;

FIG. 4 is a rear elevational view thereof; and

FIG. 5 is a left side elevational view thereof, the right side being a mirror image of that shown.

*Fig. 1**Fig. 2**Fig. 3**Fig. 4**Fig. 5*
